UNITED STATES PATENT OFFICE.

MICHAEL H. RUSSELL, OF LAKE WORTH, FLORIDA.

STOCK ELEVATOR AND LOADER.

Application filed July 7, 1926. Serial No. 120,943.

The primary intention of the invention is the provision of apparatus for lifting and loading swine, or other stock, from a pen into a rack, wagon, car, or other carrier for transportation and shipment.

A further purpose of the invention is to provide a hoisting mechanism for raising and lowering loads generally and which is equally well adapted for use in conjunction with a stock yard, warehouse, store, garage, or other place where sundry articles, merchandise and the like is required to be elevated, or lowered and the same may be installed as a permanent fixture.

While the drawings illustrate a preferred embodiment of the invention it is to be understood that in adapting the means to meet specific needs and requirements the design may be varied, and such other changes in the minor details of construction may be resorted to within the scope of the invention as claimed, without departing from the spirit thereof.

For a full understanding of the invention and the merits thereof, reference is to be had to the following description and the drawings hereto attached in which,

Figure 1 is a side view of a hoisting mechanism embodying the invention, parts being broken away,

Figure 2 is a horizontal sectional view on the line 2—2 of Figure 1,

Figure 3 is a transverse sectional view on the line 3—3 of Figure 1, looking in the direction of the arrows,

Figure 4 is a fragmentary sectional view on the line 4—4 of Figure 1, looking in the direction of the arrows, showing the parts on a larger scale, and

Figure 5 is a detail sectional view on the line 5—5 of Figure 1.

Corresponding and like parts are referred to in the following description and designated in the several views of the drawings by like reference characters.

The apparatus comprises a suitable framework, a load carrier, and an elevating and lowering mechanism. The supporting framework includes corner posts 1, longitudinal sills 2, end sills 3, upper side rails 4, and intermediate uprights 5 connecting the upper side rail 4 and longitudinal sill 2 at one side. Suitable braces 6 connect the corner posts 1 with the rails 4 and sills 2. Upper end rails 7 connect the corner posts 1 to insure the formation of a substantial structure. The

load carrier comprises a platform 8 which is strengthened and reinforced from below by bolsters 9 and this load carrier may be of any construction depending upon the particular application of the mechanism and the special use for which the same is designed. A rim 10 extends vertically from the ends and sides of the platform 8 and may project to any determinate height therefrom. The rim 10 constitutes a guard. The side portions of the rim, or guard 10 are fixed, whereas the end portions are removable for ready access to and egress from the platform. Side panels 11 and end panels 11^a enclose the platform to prevent stock leaping therefrom when the apparatus is in service, and elevating cattle from a pen into position for loading upon a wagon, or other carrier. These panels are preferably detachable and the end panels 11^a are connected to the end guards 10 which are removable therewith to facilitate the entrance of stock upon the platform and their exit therefrom in the operation of loading and unloading. The enclosing panels may be of any preferred construction and, as shown, consist of spaced horizontal strips and pairs of vertical strips, or battens 12 between which the horizontal strips are secured, the lower ends of the vertical strips, or battens 12 embracing opposite sides of the guard 10. As shown most clearly in Figure 3, the lower ends of the pairs of vertical strips, or battens 12 loosely engage opposite sides of the guard 10 along the side of the platform 8, whereas the lower ends of the strips, or battens 12 applied to the end panels 11^a are permanently secured to the guard 10 at the ends of the platform 8, so that the end panels and guards are detachable, as a unit, or gate. Angle brackets 13 are secured to the ends of the side panels 11 and are disposed to embrace opposite sides of the panels 11 and 11^a at the corners, as shown most clearly in Figure 2.

The load carrier is mounted to move vertically on the corner posts 1 and is directed in its vertical movements by guide rollers 14 which are disposed to engage the inner adjacent sides of the corner posts, as shown most clearly in Figure 4, and in this manner lateral and longitudinal displacement of the load carrier is prevented. The guide rollers 14 are mounted in suitable brackets 15 attached in any preferred and substantial way to the corner portions of the platform or bed of the load carrier. As means for

raising and lowering the load carrier, screws 16 are provided and extend between the upper side rails 4 and the longitudinal sills 2. Two elevating screws 16 are located at each side of the apparatus and are connected for simultaneous movement. Each of the elevating screws 16 is mounted at its ends in the rails 4 and sills 2 substantially, as shown in Figure 5, in which is shown a flanged socket 17 and a journal 18, the latter consisting of a reduced end of the screw 16. A washer 19 is mounted upon the base portion of the journal 18 and both the washer and socket 17 are formed with matching annular grooves to provide a race in which balls 20 are located to provide an antifriction bearing. A bevel gear 21 is fast to the lower end of each of the elevating screws 16 and is in mesh with a companion bevel gear 22 fast to the outer end of a longitudinal shaft 23. There are two longitudinal shafts 23 at each side of the apparatus and they are disposed in longitudinal alignment and are geared at their inner ends to a transverse shaft 24 which is located below the platform 8 and extends beyond the sides thereof, as shown most clearly in Figure 2, the projecting ends being provided with bevel gears 25 which are in mesh with companion bevel gears 26 secured to the inner ends of the aligned longitudinal shafts 23. The transverse shafts 24 may be operated from a suitable source of power to effect an elevating, or a lowering of the load carrier. As shown, a sprocket wheel 27 is connected by a drive chain 28 to a sprocket wheel 29 fast to an end of the transverse shaft 24. The sprocket wheel 27 is fast to a shaft which is mounted in a cross piece 30 connecting the uprights 5 and which shaft, for convenience, is provided with a crank 31, whereby the mechanism may be operated by hand. A nut 32 is mounted upon each of the elevating screws 16 and operates therewith to effect a vertical movement of the load carrier, to which the nuts 32 are connected. An L-bracket 33 is provided for each of the nuts 32 and is pivoted thereto, as indicated at 34. The brackets 33 are disposed so that their horizontal members engage under the ends of certain bolsters 9 to which they are made fast, whereas the vertical members extend along the outer sides of the side guards 10

to which they are connected in any preferred way. By having the nuts 32 pivotally connected to the load carrier the latter may receive a limited vibratory movement without imposing undue strain upon the elevating screws.

When the apparatus is adapted for loading stock, it is arranged with one end opposite the chute, or opening of the pen or enclosure to admit of the cattle passing from the pen to the platform 8. The wagon, or other carrier is located at the opposite end of the apparatus to receive the cattle therefrom. After the platform 8 has received the desired load, the entrance thereto from the pen may be closed by replacing the end panel or gate previously removed and the platform is elevated by operating the crank 31 which, through the instrumentalities herein set forth, effect a lifting of the platform to the required elevation and the cattle are loaded into the wagon, or other carrier by removing the end panel or gate 11^a at the outer end of the apparatus. In order that the cross piece 7 at the delivery end may not interfere with the passage of the stock from the platform to the wagon, the corner posts 1 at the delivery end project to a greater height than the corner posts 1 at the receiving end of the apparatus. It is evident from the foregoing and the drawings hereto attached, that the apparatus is readily adapted as an elevator for use in stores, warehouses, garages and other places where loads, articles and commodities are required to be raised, or lowered.

Having thus described the invention, I claim:

In a hoisting mechanism of the character specified, comprising a frame-work, a load carrier, mounted within the frame work for vertical movement and comprising a bottom, a guard surrounding the bottom, bolsters disposed beneath the said bottom, angle brackets attached to the bolsters and guard, elevating screws mounted upon the frame-work and nuts mounted upon the elevating screws and pivoted to the said angle brackets.

In testimony whereof I affix my signature.

MICHAEL H. RUSSELL. [L.S.]
